UNITED STATES PATENT OFFICE.

GEORGE E. DAVIS, OF FARMERSVILLE, CALIFORNIA.

DESIGN FOR A WATCH-FOB.

No. 39,988.

Specification for Design.

Patented May 18, 1909.

Application filed February 6, 1909. Serial No. 476,569. Term of patent 7 years.

To all whom it may concern:

Be it known that I, GEORGE E. DAVIS, a citizen of the United States of America, residing at Farmersville, in the county of Tulare and State of California, have invented a new, original, and ornamental Design for Watch-Fobs, of which the following is a specification.

The figure is a plan view of a watch fob showing my new design.

I claim:

The ornamental design for a watch fob as shown.

GEORGE E. DAVIS.

Witnesses:

JOHN ROYAL BATES,
C. R. McEVERS.
